UNITED STATES PATENT OFFICE

138,741

DESIGN FOR A COMBINATION BATHROOM UNIT

Louis W. Helmuth, Sr., Lakewood, Ohio, assignor to The Midland Steel Products Company,
Cleveland, Ohio, a corporation of Ohio

Application May 29, 1944, Serial No. 113,786

Term of patent 14 years

(Cl. D4—4)

To all whom it may concern:

Be it known that I, Louis W. Helmuth, Sr., a citizen of the United States, residing at Lakewood, in the county of Cuyahoga and State of Ohio, have invented a new, original, and ornamental Design for a Combination Bathroom Unit, of which the following is a specification, reference being had to the accompanying drawing, forming a part thereof.

Fig. 1 is a perspective view of the combination bathroom unit showing my new design with the mirrored lid open.

Fig. 2 is a similar view of the same viewed from the other end, and,

Fig. 3 is a front elevation of the design with the mirrored lid in closed position.

I claim:

The new, original and ornamental design for a combination bathroom unit, substantially as shown.
